CLAIM

The ornamental design for a rooftop mounted portable shower unit, as shown and described.

DESCRIPTION

FIG. 1 is a top front left perspective view of a rooftop mounted portable shower unit of the present invention; FIG. 2 is a bottom back right perspective view thereof; FIG. 3 is a right side view thereof; FIG. 4 is a left side view thereof; FIG. 5 is a bottom view thereof; FIG. 6 is a top view thereof; FIG. 7 is a front view thereof; FIG. 8 is a back view thereof; and, FIG. 9 is a bottom back right perspective view thereof, illustrating the rooftop mounted portable shower unit mounted on a vehicle and in use. The broken lines shown in FIG. 9 depict environment and form no part of the claimed design.
